UNITED STATES PATENT OFFICE

SPENCER HEATH, OF ELKRIDGE, MARYLAND, ASSIGNOR TO THE AMERICAN PROPELLER COMPANY, OF BALTIMORE, MARYLAND, A CORPORATION OF MARYLAND

PROPELLER

Application filed December 31, 1925. Serial No. 78,659.

This invention relates generally to propellers for aircraft and particularly to propellers having metal blades.

One object of my invention is to provide a propeller in which the blades are hinged or pivotally connected to the hub. It has been found that propeller blades made of metal very frequently fail or break due to crystallization or fatigue of the metal near the hub 5 which results from the constant flexing of the metal caused by the intense vibration of the blades. By providing a hinge or pivotal connection between the blade and hub, the vibrations of the blade are absorbed in the 10 hinge and the flexing of the metal in the blades is thus obviated.

A further object of my invention is to provide a construction in which the axes of the 15 hinges between the blades and hub are arranged obliquely to the plane of rotation of the propeller. This arrangement simplifies the forming of the blades by reducing the amount of twist which must be given to the metal, and it, furthermore, serves to reduce 20 the end thrust on the hinges due to the torque of the engine or propeller shaft.

Another object of my invention is to provide a construction in which the axes of the 25 hinges between the blades and hub may be angularly adjusted relative to the plane of rotation of the propeller blades and secured in any desired position of adjustment.

A further object is to provide a hinge connection between the hub and blades which 30 will permit a slight degree of pivotal or hinge action without any sliding friction between the parts.

A still further object is to provide yieldable means for maintaining the blades in a 35 substantially radial position while the propeller is at rest.

A still further object is to provide a strong and rigid construction for the inner or base 40 portion of the blades and also to provide detailed improvements in the hinge connection between the base of the blades and the hub.

A still further object is to provide certain 45 improvements in the construction of the blades themselves.

The objects and advantages of my invention will be more fully understood from the following specification and the accompanying drawings forming a part thereof and in which one specific embodiment of the invention is disclosed, it being obvious that changes and modifications in this construction may be made within the spirit of the invention. In the accompanying drawings:

Figure 1 is a front elevation of a propeller 60 embodying my invention, the ends of the blades being cut away,

Figure 2 is a transverse section on the line 2—2 of Figure 1,

Figure 3 is a longitudinal section on the 65 line 3—3 of Figure 2,

Figure 4 is a longitudinal section on the line 4—4 of Figure 2,

Figure 5 is a longitudinal section showing 70 a double-walled one piece type of blade,

Figure 6 is a transverse section of the blade shown in Figure 5,

Figure 7 is a detailed section showing one 75 of the spacing and securing devices employed between the walls of the double-walled blade,

Figure 8 is a fragmentary longitudinal section substantially on the line 8—8 of Figure 3 showing certain details of the hinge constructions,

Figure 9 is a view similar to Figure 8, so 80 showing a somewhat modified construction,

Figure 10 is another view similar to Figure 8 showing a further modified construction,

Figure 11 is an elevational view of a modified form of blade having the body thereof 85 formed with a single wall, and

Figure 12 is a longitudinal section on the line 12—12 of Figure 11.

Referring to the drawings in detail by 90 the reference characters thereon, A indicates an engine shaft on which the propeller is mounted. The hub of the propeller is preferably formed of an inner member 10 and outer members 10A, the former being rigidly connected to the engine shaft A and the latter carry the blades 11, any desired number of which may be employed. The inner member 10 of the hub is provided with externally threaded reduced portions 10B and 10C

the outer members 10A are provided with socket portions 10C, similarly threaded, and adapted to be screwed down over the threaded portions 10B. By this arrangement, it is evident that the outer members 10A of the hub may be rotated or angularly adjusted relative to the inner member 10. To secure the outer members 10A in any desired position of adjustment relative to the member 10, I provide clamping bands 10D, which surround the socket portions 10C on the outer members 10A of the hub. Each of the bands 10D is preferably formed of two portions which are provided with mating ears for receiving bolts 10E by which the ears may be drawn together and the bands tightened. To permit the walls of the sockets 10C being clamped tightly against the portions 10B of the member A, said walls are provided with slots 10F, preferably at diametrically opposite points. The bands 10D are preferably provided with a flange 10G which is adapted to cover any space left between the inner ends of the socket portions 10C and the adjacent portions of the inner member 10. The bands 10D are accurately positioned on and are movable with the sockets 10C by means of keys K so that the space between the ears of the bands will always lie opposite the slots 10F. The flanges 10G are preferably marked with graduations 10H for accurate setting or positioning of the blades.

The blades 11 are hingedly or pivotally connected to the members 10A of the hub by the arrangement now to be described. Each member 10A is provided with two outwardly projecting spaced hinge knuckles 12 having aligned openings 13 for receiving a hinge pin. The inner or base portion of each blade 11 is provided with two slots 14 spaced to correspond to the distance between the inner walls of said knuckles 12 and of a width substantially equal to the thickness thereof. The two slots 14 produce three spaced ears or arms 15 on each blade, the central one of which is adapted to lie between the two knuckles 12 and the outer ones adapted to lie against the outer surface of the knuckles 12. The arms or ears 15 of the blades are also provided with aligned openings corresponding to openings 13 in the ears 12. A hinge pin 16 is inserted through the openings in the knuckles 12 and ears 15, this pin having washers 16A at each end and also having a nut 16B threaded on one end thereof for holding it in place. Preferably hardened bushings 17 are arranged in the knuckles 12 around the hinge pin 16, these bushings preferably having a tight fit on the pins 16 but being free to rotate in the openings 13.

In the drawings, the engine shaft A is assumed to be horizontal, member 10 which is perpendicular to and extends radially from

shaft A is shown in a vertical position, and hinge pin 16 is shown in a horizontal position. Hinge pin 16 is illustrated in a substantially symmetrical position with respect to member 10 and to blade 11, and it is obvious that a vertical line extending radially from the axis of the engine shaft would lie at right angles to hinge pin 16 and intersect it at substantially its middle.

From the construction thus far described, it is evident that the axes of the hinge pins 16 can be adjusted relative to the plane of rotation of the propeller blades, this being accomplished by the angular adjustment of the outer members 10A of the hub relative to the inner member 10. Normally the axes of the hinge pins 16 are arranged obliquely to the plane of rotation of the blades. This arrangement, as previously noted, reduces the amount of twist which must be given to the metal in forming the blades and it has the additional advantage of reducing the end thrust on the hinges which results from the torque applied by the engine shaft. This is an important feature because the torque applied to the propeller is not constant but intermittent due to the successive impulses from the motor.

With the blades hinged to the hub as previously described, it will be understood that while the propeller is running, the centrifugal force, which is very great, will serve to maintain the blades in a radial or operative position. To prevent the blades from falling over or about their hinges when the propeller is at rest, I provide the following arrangement. Each blade adjacent its base has secured thereto a plate 18 the end portions of which form projections extending laterally on each side of the hinge pin 16, the central portion of said plate being bent to conform to the curved portion of the blade surrounding the pin. The plate 18 is preferably secured to the blade by means of spring clamping arms 18A welded to the plate 18 and so arranged as to closely embrace the base of the blade. Beneath each end of said plate 18 is arranged a resilient member 19, which may be pads of rubber, coiled springs or any other suitable device. The members 19 are preferably attached to the under side of said plate, in any desired manner. The lower surfaces of the members 19 are preferably spaced a slight distance from the bottom of the recess in which they are placed, as indicated at 18B. This permits slight pivotal motion of the blades about the pins 16 without compression of the members 19, but when the blades are at rest the arrangement described will hold the blades substantially in a radial position.

With the blades hinged to the hub as described it is important that the hinge pins be permitted a limited amount of pivotal movement relative to the ears 12 without any

sliding contact between the parts because such sliding frictional contact may cause the contacting surfaces to "gall" and seize thus stiffening or rendering inoperative the hinge connection and leaving the blades subject to rapid flexing near the hub with resultant fatigue and fracture of the metal after a short time. To accomplish this result and insure a slight degree of flexibility at the hinge at all times I provide the various arrangements illustrated in Figures 8, 9 and 10 of the drawings. It will be understood that the hinge pin 16 is preferably fixed in the ears 15 at the base of the blades 11. Therefore, in order to take up the vibrations of the blade, the pins 16 must be capable of slight rotation relative to the knuckles 12 on the hub without sliding contact between these parts. In the form shown in Figure 8 this is accomplished by simply making the openings 13 in the knuckles 12 slightly larger than the pin 16 and the bushings 17 surrounding the same. The space or clearance between the bushing and the wall of the openings 13 is shown at 21. It is evident that this arrangement will permit a slight degree of rolling motion of the pin 16 and the bushing 17 in the opening without any sliding friction between the parts. In the form shown in Figure 9, the pin 16 is also made slightly smaller than the openings 13 and provided with an angular or knife-edge portion 22 which is adapted to bear against the inner wall of the openings 13. This arrangement also permits slight rolling action of the pin 16 relative to the knuckles 12 without sliding contact. In Figure 10, the openings in the knuckles 12 are provided with ball or roller bearings 23 which are adapted to receive the thrust of the hinge pin 16 and permit rotation of the same relative to the knuckles 12 without sliding contact.

It will thus be seen that the construction illustrated in Figs. 8 and 9 will permit a limited rolling action of the pins 16 in the openings 13 without any sliding contact taking place between the parts. This limited rolling action will serve to take up the limited and rapid vibrations of the blades and thus any danger of the hinges "seizing" or becoming rigid is obviated. The construction shown in Fig. 10 accomplishes the same result by obviating any danger of sliding frictional contact between the pins 16 and the knuckles 12.

In addition to the features heretofore described, my invention contemplates certain detailed improvements in the construction of the blades which render them specially applicable to my hinged-blade propeller. In Figs. 1 to 10 inclusive of the drawings there are shown one piece blades having double-walls, the detailed construction of this form of blade being more fully illustrated in Figs. 5, 6 and 7. In Figs. 11 and 12

a single wall blade is shown, that is one formed of a single piece but of single thickness only.

In forming the double-wall blade, I preferably employ a single piece of sheet material longer than the length of the blade to be produced. The material is tapered from the center toward each end and from one edge toward the other. The width of the sheet at various points from the center toward each end is such as to produce a blade of the desired width. The sheet thus formed is bent at its center 11A, Fig. 5, and the edges of the overlying straight portions 11B are welded or otherwise secured together, as indicated at 11C. The portions 11B are, of course, given the desired twist and contour before being bent upon each other which may be done by pressing or in any other suitable manner. In order that the walls 11B of this form of blade may be properly spaced and also held against separation, a plurality of threaded studs 11D are threaded through one of the walls 11B and these studs are provided with reduced ends 11E which are adapted to project through countersunk holes in the opposite wall 11B and be riveted over. This arrangement effectively prevents collapse or separation of the spaced walls 11B. It will be understood that the bent portion 11A of this form of blade is shaped to closely fit the hinge pin 16 and also that the base of the finished blade is provided with the slots 14 and ears 15, as previously described.

The single-wall blade illustrated in Figs. 11 and 12, is formed of a single piece of suitably shaped metal which preferably tapers from base to tip and from the back to the front and bent to produce the desired twist.

Whether formed of single wall or double wall, the basal portion of the blade is preferably held between the arms of a hinge loop 24 the middle portion of which is slotted to receive the hub knuckles 12. The arms of the hinge loop 24 are secured to the front and back sides of the blade bases preferably by welding or brazing indicated at 25. In connection with the double wall blade the hinge loop 24 follows the bend of the blade around the hinge pin and contacts with the blade base, reinforcing it throughout the length of the hinge loop. In connection with the single wall blade, the hinge loop is preferably thicker and forms the entire blade structure surrounding the hinge pin, only the two arms of the hinge loop being welded or otherwise secured to opposite sides of the single wall blade base.

Having thus described my invention, what I claim as new and desire to be secured by Letters Patent is:

1. A propeller having a hub provided with outwardly projecting knuckles, a blade having slots at its base for receiving said knuckles, and a hinge pin passing through said

knuckles and through the base of the blade, whereby the blade is hingedly connected to the hub.

2. A propeller blade structure in which 5 the blade is formed of a sheet of material transversely bent intermediate its ends and its two unbent portions being brought together and secured to each other to form the opposite sides of the blade, and a loop embracing the base of the blade, the ends of the 10 loop being secured to the sides of the blade.

3. In a propeller, in combination, a hub, 15 a blade, a hinge pin for connecting said hub and blade, and means for connecting said pin to the hub and blade, to roll slightly upon one of said parts upon slight rotation of the blade about the axis of the pin.

4. In a propeller, in combination, a hub 20 and a blade connected by a hinge pin, said pin tightly engaging one of said parts, the other of said parts having openings slightly larger than said pin, whereby the pin may roll slightly on said last named part upon slight rotation of the blade about the axis 25 of said pin.

5. In a propeller, in combination, a hub having spaced hinge knuckles thereon provided with aligned openings, a blade having an ear arranged between said knuckles, 30 a hinge pin mounted in said openings and passing through said ear, said pin being slightly smaller than said openings, to permit slight rolling motion of the pin relative to said knuckles.

35 6. In a propeller, in combination, a hub having spaced hinge knuckles thereon provided with aligned openings, a blade having an ear arranged between said knuckles, a hinge pin mounted in said openings and 40 passing through said ear, said pin being slightly smaller than said openings and having an angular portion adapted to bear against the inner wall of said openings, whereby slight rolling motion of said pin 45 relative to said knuckles is permitted.

7. In a propeller, the combination of a hub, 50 a hinge pin mounted thereon, and a blade swingable around the axis of said hinge pin comprising a sheet of metal bent around said hinge pin and forming opposite side portions of said blade.

8. In a propeller, the combination of a hub, 55 a hinge pin mounted thereon, a blade swingable around the axis of said hinge pin comprising a sheet of metal bent around said hinge pin, and a sheet metal reinforcing member bent around said hinge pin and embracing both sides of the inner portion of 60 said blade.

65 9. In a propeller, the combination of a hub having hinge portions, a hinge pin connected to said hinge portions, and a blade swingable around the axis of said hinge pin comprising a sheet of metal bent around said hinge pin, and a sheet metal reinforcing

member bent around said hinge pin and embracing both sides of the inner portion of said blade, the inner end of said blade and said reinforcing member being slotted to receive the co-acting hinge portions on the hub. 70

10. In a propeller, the combination of a hub, a hinge pin mounted thereon, a blade swingable around the axis of said hinge pin, and a sheet metal member bent around said hinge pin and embracing both sides of the 75 hub portion of said blade.

11. In a propeller, the combination of a hub having hinge portions, a hinge pin connected to said hinge portions, a blade swingable around the axis of said hinge pin, and 80 a sheet metal member bent around said hinge pin and embracing both sides of the hub portion of said blade, the inner end of said sheet metal member being slotted to receive the co-acting hinge portions on the hub. 85

12. In a propeller, a hub adapted to receive a propeller shaft, a hinge pin carried by said hub at right angles to and intersected by a line extending radially from the axis of the propeller shaft, said hinge pin being 90 arranged to be fixed obliquely to the plane of rotation of the propeller at an angle which is constant for all speeds of rotation of said hub, and a rigid blade swingable about the axis of said hinge pin. 95

13. In a propeller, a hub adapted to receive a propeller shaft, a hinge pin carried by said hub at right angles to and intersected at substantially its middle by a line extending radially from the axis of the propeller shaft, said hinge pin being arranged to be fixed obliquely to the plane of rotation of the propeller at an angle which is constant for all speeds of rotation of said hub, and a rigid blade swingable about the axis of said 100 hinge pin. 105

14. In a propeller, a hub adapted to receive a propeller shaft, a hinge pin carried by said hub at right angles to and intersected by a line extending radially from the axis of the propeller shaft, said hinge pin being arranged to be fixed obliquely to the plane of rotation of the propeller at an angle which is constant for all speeds of rotation of said hub, means for selectively adjusting the angle 110 of obliquity of said hinge pin, and a rigid blade swingable about the axis of said hinge pin. 115

15. In a propeller, a hub adapted to receive a propeller shaft, a hinge pin carried by said hub at right angles to and intersected at substantially its middle by a line extending radially from the axis of the propeller shaft, said hinge pin being arranged to be fixed obliquely to the plane of rotation of the propeller at an angle which is constant for all speeds of rotation of said hub, means for selectively adjusting the angle of obliquity of 120 said hinge pin, and a rigid blade swingable about the axis of said hinge pin. 125

16. In a propeller, a hub adapted to receive a propeller shaft, a hinge pin carried by said hub at right angles to and intersected by a line extending radially from the axis of the propeller shaft, said hinge pin being arranged to be fixed obliquely to the plane of rotation of the propeller shaft at an angle which is constant for all speeds of rotation of said hub, a rigid blade swingable about the axis of said hinge pin, and resilient means for preventing the blade from moving out of a substantially radial position.

17. In a propeller, the combination with a hub and a blade hinged thereto, of a resilient member on one side of the hinged connection and adapted to be compressed by a movement of the blade in the direction of said member and away from a radial position, said blade having a slight freedom of pivotal movement without compressing said resilient member.

18. In a propeller, the combination with a hub and a blade hinged thereto, of a pair of resilient members one on each side of the hinged connection, each of said resilient members being adapted to be compressed by a movement of the blade in the direction of said member and away from a radial position, said blade having a slight freedom of pivotal movement without compressing either of said resilient members.

19. In a propeller, the combination with a hub and a blade hinged thereto, of a plate mounted on said blade and extending laterally from each side of the inner end thereof, a resilient member interposed between each end of said plate and said hub, each of said resilient members being adapted to be compressed by a movement of the blade in the direction of said member and away from a radial position, said blade having a slight freedom of pivotal movement without compressing either of said resilient members.

In testimony whereof I hereunto affix my
45 signature.

SPENCER HEATH.
